SUPERFLUOUS HAIR REMOVER

Leslie D. Bendure, Seattle, Wash.

Application October 27, 1938, Serial No. 237,339

1 Claim. (Cl. 51—186)

This invention relates to toilet articles and more particularly an instrument for removing superfluous hair from the body or limbs of individuals.

5 The primary object of this invention resides in the provision of an instrument for removing superfluous hair from the limbs or body of an individual by a harmless abrasive carried thereby.

Another object of this invention resides in the 10 provision of an instrument of this character preferably of paddle configuration to permit a secure grip thereof with either hand so it can be readily applied to any part of the body in removing superfluous hair.

15 A further object of this invention resides in the provision of an instrument of this character adapted to be operated in a circular or other motion in removing superfluous hair from the body or limbs.

20 A still further object of this invention is the provision of an attractive instrument of this character adapted to remove superfluous hair from the body or limbs without irritation of the skin.

25 Aside from the above objects this invention resides in the provision of an instrument of this character which when operated produces no odors and remains in a sanitary condition.

With these and other objects in view this 30 invention resides in certain novel features of construction and arrangement of elements to be hereinafter set forth in the specification, illustrated in the accompanying drawing and pointed out in the claim and, while this disclosure depicts my present conception of the invention, the right is reserved to resort to such changes in construction and arrangement of elements as come within the scope of the claim.

35 In the accompanying drawing forming a part of this application.

40 Fig. 1 is a plan view of a hair removing instrument construction in accordance with this invention.

Fig. 2 is a longitudinal sectional view thereof 45 approximately on line 2—2 of Fig. 1.

Fig. 3 is a sectional view of a modified form of the instrument showing the abrasive substance impregnated therein.

50 In the present embodiment of this invention, the numeral 5 designates, in general, an instrument preferably for removing superfluous hair

from the body or limbs of an individual and consists of a piece of material having a substantially rectangular head 6 provided with a handle 7.

The head 6, as illustrated in Figs. 1 and 2, is adapted to be covered by a sleeve 8 of suitable 5 material having its outer surfaces coated or otherwise treated with an abrasive substance 9 and is herein retained on the head through the instrumentality of a bead 10, formed along its open edge, adapted to seat in a groove 11 formed 10 in the head and, while this method is employed to secure the sleeve on the head, it is to be understood such other methods of securing the same to the head may be employed as come within 15 the scope of the claims.

Fig. 3 of the drawing discloses a similarly shaped instrument having the opposite sides of its head coated, impregnated or otherwise treated with an abrasive substance indicated at 15 and, while the abrasive is herein recited as being on both sides of the instrument, it is within 20 the purview of this invention to dispose it on one side only.

With this invention fully set forth it is manifest that an instrument for removing superfluous 25 hair from the body or limbs of an individual is provided and, through the simplicity of the construction thereof, the same can be cheaply manufactured and sold at a reasonable price.

Having thus described my invention, what I 30 claim and desire to protect by Letters Patent is:

As a new article of manufacture, an instrument 35 for removing hair from the body and limbs of a person comprising a body of this material having opposed flat faces and consisting of a substantially rectangular head merging at its rear end into a handle extending rearwardly from the head longitudinally thereof midway the width of the head, the head being formed adjacent its rear end with a continuous groove extending on both sides and ends thereof, a sleeve of flexible material fitting snugly about the head in enclosing relation thereto and being closed at its front end, the rear end of said sleeve being open for insertion of the head and about its 40 rear end having a beaded rear marginal edge fitting snugly into said groove to hold the sleeve in place about the head, and a coating of fine abrasive material for the outer surface of said sleeve constituting hair removing means.
